Patented Feb. 18, 1919.

Inventor
MAX KNOPP

By his Attorney

Morris Fischbacher

UNITED STATES PATENT OFFICE.

MAX KNOPP, OF NEW YORK, N. Y.

HYDRAULIC MOLD.

1,295,042.

Specification of Letters Patent. Patented Feb. 18, 1919.

Application filed May 11, 1918. Serial No. 233,889.

To all whom it may concern:

Be it known that I, MAX KNOPP, a citizen of the United States, and resident of New York city, in the county of Kings and State of New York, have invented certain new and useful Improvements in Hydraulic Molds, of which the following is a specification.

This invention relates to hydraulic molds used in blocking and shaping hats. These 10 hydraulic molds are used in conjunction with hydraulic presses in the lower stationary half of which is held a die usually of metal on which the mold fits. The upper half of the press is movable vertically so as to be 15 pressed down against the lower half and is provided with an expansible rubber water bag which extends into the crown of the hat in the pressing operation. Molds of the character herein referred to have heretofore 20 been made of leather, but numerous difficulties have been had with the leather mold. Thus very often in the pressing operation the rubber water bag is punctured and the hot water runs out on the leather mold and 25 burns it, practically ruining it so that it is no longer available for further use. The leather, furthermore softens under the influence of the moisture and in very short time the mold loses its shape and becomes 30 useless. The leather molds furthermore are very expensive, both as to the initial cost and from the stand point of the life of the mold.

Among the objects, therefore, of my present 35 invention is to provide a hydraulic mold for the purpose described of such construction that it shall not be in any way affected as to usefulness by the hot water that may run out of the rubber bag and to further provide 40 a mold of such construction that it may be available for reuse after having once been used in the hydraulic press and moistened thereby. A further object of the present invention is to provide a hydraulic mold of 45 the character described which shall retain its shape under long use, be durable and yet be cheap to manufacture and simple in construction.

Further objects and advantages of this invention will appear from the detailed description and the features of novelty will be particularly pointed out in the claims.

In the drawing accompanying this specification and forming a material part thereof. 50 Figure 1 is a perspective view of my newly improved mold.

Fig. 2 is a transverse cross-section thereof showing the mold in place on the die (shown dotted) and,

Fig. 3 is a longitudinal cross-section drawn 60 on a similar scale.

The mold referred to in this specification usually comprises a shaped body portion adapted to fit on the die in the lower half of the hydraulic press and an extension to 65 which may be secured a crown portion shaped to conform to the crown of a hat of a given style. In the use of this mold the hat is fitted thereon, the brim resting against the brim portion of the mold and the crown 70 of the hat fitting over the crown portion attached to the extension. With this preliminary explanation, the particular embodiment of my invention shown in the drawing will now be understood.

Referring in detail to the drawing, my newly improved mold is seen to consist of the shaped body portion 10 formed with the extension 11 to which may be secured a crown portion 12 (not shown in full). As 80 will be clear the body portion 10 is shaped to conform to and to receive the brim of the hat and to fit on the die in the press, as clearly shown in the drawing. The invention resides in the particular material of 85 which the body portion and extension is made whereby the various objects and advantages hereinbefore set forth are attained. In the particular embodiment shown in the drawing the body portion 10 is made from inner 90 layers 13 of canvas covered by the outer layers 14 of similar material such as buckram. To secure stiffness and to insure these layers holding together I preferably place therebetween some suitable cementing and 95 stiffening material 14' which may melt under the influence of heat. For this purpose I have found gelatin the best adapted but no doubt other materials may be used. I have found, however, that gelatin is particularly 100 of advantage in that it helps the mold to retain the desired shape. After having been moistened by use in the press, I have found that upon drying the gelatin again hardens and the whole form resumes its original 105 shape with all the necessary stiffness, and the mold becomes available for reuse just as if it were new.

The extension 11 comprises a downturned portion of the body bounding the opening 110 15 therein usually elliptical in shape. The outer layers of material of the extension 11

are integral with the body portion and formed from the same pieces of buckram or canvas. However, between the inner layer 13 and the outer layers 14 of the extension 5 I insert a comparatively thick layer 16 of some stiff adhesive material such, for example as cooked rubber. This layer tapers down from the beginning of the extension beyond the end of the inner layer of canvas 10 13 and unites with another layer 17 of similar adhesive material which coöperates therewith to secure thereto the crown portion 12 usually made of vulcanized rubber. The latter it will be clear is readily secured 15 to the extension under the influence of heat by a vulcanizing process. The means just described for attaching the crown have been found very effective in securing the crown to the body and at the same time providing 20 the desired stiffness and for the retaining of the desired shape.

Molds made in the way herein described and disclosed employing instead of leather, fabrics such as canvas with stiffening and 25 adhesive means between layers of material, have been found after being shaped as desired to retain this shape, remaining stiff when dry and recovering their original shape and stiffness after being moistened in 30 the press. The materials furthermore are very cheap, much more so than leather, and the initial cost is consequently materially reduced. In addition molds made according to my new construction have the 35 advantages of longer life and efficiency.

Having thus described my invention what I claim as new and desire to secure by Letters Patent is:

1. A hydraulic mold comprising a shaped 40 body portion formed from layers of fabric and means between said layers adapted to hold them together in the shape given thereto.

2. A hydraulic mold comprising a shaped 45 body portion formed from layers of fabric and adhesive stiffening means between said layers adapted to hold them together in the shape given thereto.

3. A hydraulic mold comprising a shaped 50 body portion formed from layers of fabric and gelatin between said layers adapted to hold them together in the shape given thereto.

4. A hydraulic mold comprising a shaped 55 body portion formed from layers of canvas

and gelatin between said layers adapted to hold them together in the shape given thereto.

5. A hydraulic mold comprising a shaped body portion formed from layers of fabric 60 and means between said layers adapted to hold them together in the shape given thereto and an extension integral with said body portion whereby a crown portion may be attached. 65

6. A hydraulic mold comprising a shaped body portion formed from layers of fabric and means between said layers adapted to hold them together in the shape given thereto and an extension integral with said body 70 portion whereby a crown portion may be attached, and stiffening adhesive means within said extension.

7. A hydraulic mold comprising a shaped body portion formed from layers of fabric 75 and means between said layers adapted to hold them together in the shape given thereto and an extension integral with said body portion whereby the crown may be attached, said extension comprising outer layers of 80 fabric integral with the outer layers of the body portion and a layer of adhesive stiffening material within said outer layers.

8. A hydraulic mold comprising a shaped body portion formed from layers of fabric 85 and means between said layers adapted to hold them together in the shape given thereto and an extension integral with said body portion whereby the crown may be attached, said extension comprising outer layers of 90 fabric integral with the outer layers of the body portion and a tapered layer of adhesive stiffening material within said outer layers.

9. A hydraulic mold comprising a shaped 95 body portion formed from layers of canvas and gelatin between said layers adapted to hold them together in the shape given thereto, and an annular extension integral with said body portion comprising outer layers 100 of canvas and an inner canvas layer of lesser width than said outer layers and a tapered layer of cooked rubber within said extension extending beyond said inner layer whereby a crown portion may be vulcanized to said extension. 105

Signed at New York city, in the county of New York and State of New York this first day of May, A. D. 1918.

MAX KNOPP.
